REFRIGERATING APPARATUS

Application filed June 10, 1927. Serial No. 197,788.

This invention relates to refrigerating systems, and more particularly concerns apparatus for use in connection with the refrigeration element of heat absorbing unit of a refrigeration system of the compression type.

Refrigerating systems of the compression type include a refrigeration element located in a cooling chamber and supplied with a liquid refrigerant, which, upon changing to the gaseous state within the refrigeration element produces the desired heat absorbing or cooling effect. The system includes a pump or compressor for compressing the gasified refrigerant, a condenser for cooling and liquefying the compressed refrigerant and a pressure-reducing valve through which the liquefied refrigerant passes to the refrigeration element. A rotary pump is suitable for use as a means for compressing the gasified refrigerant, and when such a pump is used, it is necessary to provide a suitable sealing fluid, such as oil, for sealing the movable joints in the pump mechanism. Due to the heat generated in the pump and to the rush of compressed refrigerant therethrough, a certain amount of the sealing fluid forms into minute particles and is carried with the refrigerant into the condenser and ultimately into the refrigeration element. In this manner, the sealing fluid accumulates in the refrigerating element, thereby depriving the pump of an effective sealing means and reducing the heat absorbing efficiency of the refrigeration element by fouling the interior surfaces thereof. Various expedients such as cooling the sealing fluid and passing the refrigerant through filtering means upon leaving the pump having been suggested and employed to maintain the sealing fluid in the pump, but a certain amount of this fluid nevertheless mingles with the refrigerant and accumulates in the refrigeration element.

With the above and other considerations in mind, it is a principal object of the present invention to provide apparatus for use in con-

nnection with the refrigeration element of a refrigerating system for extracting the sealing fluid from this element and returning this fluid to the pump. In refrigerating systems of the type concerned in this invention, the refrigerant flows into the refrigeration unit in liquid form, and there boils or gasifies and is drawn back to the compressor in gaseous form. The sealing fluid does not gasify but floats in a thin layer on the surface of the liquid refrigerant in the refrigeration unit. According to the present invention, means are provided for maintaining the mouth of an outlet pipe at all times at the level of the liquid refrigerant in the refrigeration element, thus skimming the sealing fluid from the refrigerant and returning it to the pump. In order that the sealing fluid outlet may be maintained at the surface of the liquid regardless of changes in the liquid level, the outlet is movably supported by floating means, and this float is also employed to support the outlet for the gasified refrigerant above the surface of the liquid.

Other specific objects, advantages and characteristic features of the present invention will become apparent as the description thereof progresses.

In describing the invention in detail, reference will be made to the accompanying drawings, in which;

Fig. 1 is a front elevation, partly in section of a refrigerator equipped with a refrigerating system embodying the present invention;

Fig. 2 is an elevation of the cooling chamber of the refrigerator, showing certain details of the refrigeration element;

Fig. 3 is a sectional view of the outlet valve of the refrigeration element;

Fig. 4 is a sectional side view of the cooling chamber and the refrigeration element.

Fig. 5 is a sectional plan view of the refrigeration element, showing the details of the outlet apparatus; and

Fig. 6 is an enlarged sectional view of a portion of the outlet apparatus.

Referring to the drawings, and more particularly to Fig. 1, the refrigerating system embodying the present invention has been shown installed in a refrigerator of a conventional type. This refrigerator may be of any suitable form, and as shown generally comprises an apparatus compartment A, a 10. cooling chamber C and a food or storage chamber F, the cooling and storage chambers being surrounded by suitable heat insulating walls W. The cooling chamber C and the storage chamber F are separated by a vertical 15 partition 1 having openings 2 at the top and bottom thereof as shown to permit the free circulation of air between these compartments. A plurality of shelves 3 are provided in the storage chamber F, being supported in any suitable manner from the walls of this compartment.

The compressing, condensing and pressure-reducing means of the refrigerating system are located in the apparatus compartment A. 25 The compressor comprises a suitable pump 4, preferably of the rotary or gear type, driven by an electric motor or other source of power 5 through a shaft 6. Suitable condenser coils 7 are located adjacent the pump 4, and a fan 30 8 is provided on the drive shaft 6 for cooling the condenser coils 7. Suitable ventilating openings 9 are preferably provided in the side walls of the apparatus compartment A to permit the free circulation of cooling air therethrough. A suitable pressure-reducing valve is preferably provided in connection with the system. This valve may take any suitable form, and in the embodiment shown comprises a float actuated valve V of the type described in detail in my co-pending application, Serial No. 149,844, filed Nov. 22, 1926. 40 As the valve V is not an essential element of the present invention, it will not be described herein, it being sufficient to state that this 45 valve acts to permit the liquefied refrigerant to flow into the refrigeration element at a reduced pressure.

The refrigeration element, designated as R, may take any suitable form, and as shown 50 comprises two parallel horizontally disposed drums or headers 10 and 11 connected by a plurality of rows of parallel tubes 12 which are spaced apart as shown to form freezing compartments 13 therebetween. The tubes 55 12 may be formed integrally with the headers 10 and 11, or may be secured to openings therein in any suitable manner. A large metallic block 40 is preferably located within the upper header 10, and serves to absorb 60 heat when the compressor of the refrigerating system is not in operation thereby maintaining the refrigerator at a substantially even temperature. The freezing compartments 13 are preferably provided with a plurality of shelves 14 for holding receptacles 65

in which liquids may be frozen. A front cover plate 15 having an opening 16 therein, is secured to the front of the refrigeration element R by suitable brackets 17 and 18 as shown in Fig. 4, and a door or closure 19 is hinged or otherwise suitably secured over the opening 16 and serves to close the freezing compartments 13.

The upper drum or header 10 of the refrigeration unit R is preferably formed with a removable head 22, secured to the drum by means of machine screws 23. Two openings 24 and 25 are provided in the head 22, and inlet and outlet valve fittings 26 and 27 are secured respectively over these openings by means of machine screws as shown in Figs. 3, 4 and 5. The fittings 26 and 27 are provided with cut-off valves which may be employed to isolate the refrigeration element from the remainder of the system in order that the assembly or repair of the system may be effected without loss of the refrigerant.

The valve mechanisms employed in the fittings 26 and 27 may take any suitable form, but are preferably of the type shown in detail in Fig. 3 wherein the valve mechanism of the fitting 27 has been illustrated, it being understood that the valve mechanism of the fitting 26 is preferably of similar construction. The valve construction comprises a sleeve member 28, screw threadedly secured to an opening in a valve chamber 29 formed in the fitting 27. A valve stem 30 has a threaded connection with the central bore 31 of the sleeve 28, and a suitable packing substance 32, such as oiled wicking, is compressed between the outer portion of the stem 30 and the enlarged outer bore of the sleeve 28 by means of a packing nut 33. The outer end 34 of the valve stem 30 is preferably slotted or otherwise formed for the reception of a tool for operating the valve, and the outer end of the sleeve 28 is closed by a plug 35 as shown.

Integral with or suitably secured to the inner end of the valve stem 30 is a tapered plug or gate 36. This gate is adapted when the valve stem 30 is in its inner position, to seat against and close the opening 37 of the passage 38 in the fitting 27, and when the stem 30 is in its outer or open position, to seat against and close the opening in the inner end of the sleeve 28.

With the construction described, when the valve is in its open position, the plug 36 keeps the refrigerant from entering the central bore of the sleeve 28 and thus prevents the corrosion of the metal parts or the rotting of the packing material by the refrigerant. When the valve is closed, the refrigerant is cut-off from the valve chamber 29 and hence it does not come into contact with the moving parts of the valve. Thus the valve operating and packing mechanism is only exposed to the refrigerant while being moved from

one position to the other, and because of this construction and arrangement, the life of the valve is greatly prolonged.

The construction of the outlet means for the refrigeration element, which forms an important feature of the present invention, will now be described. The inner face of the head 22 of the upper drum or header 10 is provided with an integral boss or extension 39 having a horizontal cylindrical opening 41 therein in which is journaled an elbow fitting 41. A shoulder 42 is provided on the fitting 41 to bear against one end of the boss 39, and a plug 43 is threaded into the end of the fitting as shown, this plug serving to hold the fitting within the boss 39 and to close the end of the fitting. The horizontal opening in the boss 39 communicates with the outlet opening 25 in the head 22, and an enlarged opening 44 is provided in the fitting 41 in such a position that communication between the outlet opening 25 and the interior of the fitting 41 is maintained even though the fitting is turned to an appreciable angle relative to the boss 39. A pipe 45 is secured to the free end of the angle fitting 41 and the outer end of this pipe is secured to an outlet angle fitting 46. The fitting 46 comprises a large pipe angle having an upwardly extending opening 47 and an integral extension 48 with a circular opening therein as shown in Fig. 4. A small passage or opening 49 extends from the interior of the fitting 46 to the interior of the opening in the extension 48, this passage 49 being substantially in alignment with the axis of the pipe 45 as shown in Figs. 4 and 6. A spherical hollow metal float 50 is provided to support the outlet mechanism, this float having a radially disposed stud 51 thereon which is inserted within the opening in the extension 48 of the fitting 46, and clamped therein by a set screw 52. The stud 51 is provided with an angular passage 53 which connects with the passage 49 in the fitting 46 and opens into the interior of the drum 10 at a point in substantial alignment with a horizontal axis of the float 50 lying parallel to the axis of movement of the fitting 41. The outlet pipe 45, the fittings 41 and 46, and the float 50 are so constructed and arranged that the outlet opening 53 is at all times maintained at the surface of the liquid in the drum 10, the opening 47 being supported at a point well above the liquid surface as shown in Fig. 4.

As shown in Fig. 1, suitable pipes are provided for connecting the outlet of the compressor to the condenser coils 7, the coils 7 to the pressure-reducing valve V, the valve V to the inlet valve fitting 26 of the refrigeration element R, and the outlet valve fitting of the refrigeration unit to the inlet of the compressor 4. In operation, the gaseous refrigerant is compressed by the pump 4 and passes into the condenser 7 where it is cooled

and liquefied by air from the fan 8 on the motor shaft. The liquid refrigerant then passes through the valve V and flows into the upper drum 10 of the refrigeration unit R through inlet valve fitting 26. The liquid refrigerant circulates through tubes 12 and the lower header 11 of the refrigeration element, and as heat from the cooling chamber is absorbed, the refrigerant boils or gasifies and passes into the upper part of the drum 10. From the drum 10, the gaseous refrigerant passes through the opening 47 in the fitting 46, through the pipe 45, the angle fitting 41, the opening 44 and the passage 25 to the outlet valve fitting 27 and back to the pump 4, thus completing the cycle.

As stated above, a quantity of sealing fluid, such as oil, is introduced into the pump 4 to form a gas-tight seal and a lubricant for the moving parts of the pump, and a certain amount of this fluid is carried into the refrigeration element with the liquefied refrigerant. The sealing fluid floats on the surface of the refrigerant in the drum 10 and is carried back to the pump 4 through passages 53 and 49. As the opening of the passage 53 is at all times maintained at the surface of the liquid refrigerant in the drum 10, the sealing fluid floating on this surface is continuously drawn off through the passage 53 regardless of changes in the liquid level within the drum. The opening of the passage 53 is so located and of such a size that very little if any of the liquid refrigerant passes therethrough, the sealing fluid being effectively skimmed from the surface of the refrigerant by this opening. This is a highly desirable feature, as it is essential to the economical operation of the system that substantially all of the liquid refrigerant be gasified within the refrigeration unit, and that none of the refrigerant be returned to the pump in liquid form.

The described outlet means for the refrigeration element when employed in connection with a refrigerating system of the general type disclosed, effectively prevents the accumulation of sealing fluid within the refrigeration element, returning this fluid to the compressor where it again serves to lubricate and seal the moving parts thereof. At the same time, the outlet means returns only the gaseous refrigerant to the compressor, thereby enabling the system to operate in an efficient manner. The outlet means is extremely simple in construction and is therefore inexpensive to manufacture, and not likely to get out of order.

Although the refrigerating system embodying the present invention has been disclosed in connection with a single specific construction and arrangement of elements, it is to be understood that various changes, modifications, additions and omissions may be made in the construction and arrangement of both

the outlet means and the refrigerating system as a whole, without departing from the scope of the invention as defined by the appended claims.

5 I claim:

1. In a refrigerating system, in combination with a refrigeration element including a container, and means for supplying a liquid refrigerant to said container, an outlet pipe 10 for said container and means associated with said pipe for maintaining the opening of said pipe at the level of the liquid in said container, whereby the surface liquid in said container is drawn off through said outlet 15 pipe.

2. In a refrigerating system of the type employing a refrigeration unit including a container and means for supplying a liquefied refrigerant to said container, an outlet 20 for said container comprising a pipe movably mounted within said container and having an opening therein, and a float secured to said pipe adjacent said opening for maintaining said opening at the surface of the 25 liquid in the said container.

3. In a refrigerating system of the type in which a refrigerant in the liquid state is supplied to a container and gasifies within said container, an outlet means for said container 30 comprising a pipe having two openings therein, and means associated with said pipe for maintaining one of said openings at the surface of the liquid in said container to form an outlet for the gasified refrigerant and for 35 maintaining the other of said openings at the surface of the liquid refrigerant for skimming foreign matter from the surface of said liquid.

4. In a refrigerating system of the type in 40 which a compressing device containing a sealing fluid is employed to compress a refrigerant which is subsequently liquefied, supplied to a refrigerating container in the liquid state, and permitted to gasify in said container, 45 means for withdrawing the gasified refrigerant and the sealing fluid from said container comprising an outlet duct movably supported within said container, said duct having a first outlet opening therein for receiving said sealing fluid, and a second outlet 50 opening for receiving said gasified refrigerant, and means for supporting said duct with said first outlet opening at the surface of the liquid in said container and with said second 55 outlet opening above said surface.

5. In a refrigerating system of the type in 55 which a compressing device containing a sealing fluid is employed to compress a refrigerant which is subsequently liquefied, supplied to a refrigerating container in the liquid state, and permitted to gasify in said container, means for withdrawing the gasified refrigerant and the sealing fluid from said container comprising an outlet pipe movably 60 supported within said container and com-

municating with an opening in said container, said pipe having two outlet openings therein and means for moving said pipe in accordance with changes in the liquid level in said container, one of said openings being maintained at the surface of the liquid in said container and the other of said openings being maintained in a position above said surface.

6. In a refrigerating system of the type in which a compressing device containing a sealing fluid is employed to compress a refrigerant which is subsequently liquefied, supplied to a refrigerating container in the liquid state, and permitted to gasify in said container, means for withdrawing the sealing fluid from said container comprising an outlet pipe hingedly supported from one end within said container and communicating with an outlet opening in said container, said pipe having an outlet opening at a point removed from the hingedly supported end thereof, and means for maintaining said pipe in such a position relative to the liquid in said container that said opening in said pipe lies at the surface of said liquid regardless of changes in the level of said liquid.

7. In a refrigerating system of the type in which a compressing device containing a sealing fluid is employed to compress a refrigerant which is subsequently liquefied, supplied to a refrigerating container in the liquid state, and permitted to gasify in said container, outlet apparatus for withdrawing the sealing fluid from the refrigerating container comprising an outlet pipe within said container movably connected at one end in communication with an outlet opening in said container, said pipe having an opening therein adjacent the free end thereof, and a float for supporting said pipe with said opening at the surface of the liquid refrigerant in said container.

8. In a refrigerating system of the type in which a compressing device containing a sealing fluid is employed to compress a refrigerant which is subsequently liquefied, supplied to a refrigerating container in the liquid state, and permitted to gasify in said container, outlet apparatus for withdrawing the sealing fluid from the refrigerating container comprising an outlet pipe within said container movably connected at one end to said container in connection with an outlet opening in said container, and a spherical float supporting the free end of said pipe, 110 said pipe having an opening therein in substantial alignment with an axis of said float parallel to the axis of movement of said pipe.

9. In a refrigerating system of the type in which a compressing device containing a sealing fluid is employed to compress a refrigerant which is subsequently liquefied, supplied to a refrigerating container in the liquid state, and permitted to gasify in said container, outlet apparatus for withdrawing the 115

sealing fluid from the refrigerating container comprising an outlet pipe within said container, means for hingedly supporting one end of said pipe in communication with an opening in said container whereby the free end of said pipe may move vertically in said container, and a spherical float connected to the free end of said pipe, said pipe having an opening therein adjacent its free end and substantially aligned with a horizontal axis of said float lying parallel to the axis of movement of said pipe.

10. In a refrigerating system of the type in which a compressing device containing a sealing fluid is employed to compress a refrigerant which is subsequently liquefied, supplied to a refrigerating container in the liquid state, and permitted to gasify in said container, outlet apparatus for withdrawing the sealing fluid from the refrigerating container comprising an outlet pipe within said container, means for hingedly supporting one end of said pipe in communication with an opening in said container whereby the free end of said pipe may move vertically in said container, the free end of said pipe having an upwardly extending elbow with an opening therein and a second opening adjacent the corner of said elbow, and a float secured to the free end of said pipe whereby said first opening is supported above the surface of the liquid in said container and said second opening is supported at said liquid surface regardless of changes in the level of the liquid.

35 11. Outlet means for a liquid container comprising an outlet pipe pivotally mounted within said container in communication with an opening in said container and a float for supporting the free end of said pipe, said pipe having an opening therein which is maintained at the surface of the liquid in said container by said float, and having another opening above said first opening.

12. Outlet means for a liquid container comprising an outlet pipe within said container, means for pivotally supporting one end of said pipe in communication with an opening in said container, said pipe having an opening adjacent the free end thereof, and a float for supporting the free end of said pipe in a position such that said opening is maintained at the surface of the liquid in said container regardless of changes in the liquid level.

55 13. In a refrigerating system, a refrigeration unit including a container for liquid and a gaseous refrigerant, means for supplying a refrigerant to said container in liquid form, and movable means acting simultaneously to withdraw the gasified refrigerant from said container and to skim foreign liquid from the surface of the liquefied refrigerant in said container.

65 14. In a refrigerating system, a refrigeration unit compressing means for supplying

a liquid refrigerant to a container, said refrigerant gasifying within said container, and a movably mounted float supported outlet pipe within said container, said pipe having openings at different levels therein whereby the gasified refrigerant is removed from said container and foreign liquid is skimmed from the surface of the liquid refrigerant in said container.

In testimony whereof I affix my signature.

ALFRED MORRIS THOMSON.
